Des. 179,015
Patented Oct. 23, 1956

179,015

AUTOMOBILE REARVIEW MIRROR OR SIMILAR ARTICLE

George C. Knight, Detroit, Mich.

Application December 21, 1954, Serial No. 33,640

Term of patent 14 years

(Cl. D14—6)

Fig. 1 is an elevational view of an automobile rearview mirror or similar article embodying my invention.

Fig. 2 is a top plan view thereof.

Fig. 3 is a front elevational view thereof.

The characteristic features of my design reside in the portions shown by means of full lines in the drawing.

I claim:

The ornamental design for an automobile rearview mirror or similar article, substantially as shown and described.
